UNITED STATES PATENT OFFICE.

JOHN RUCKSTUHL, OF FISHKILL-ON-THE-HUDSON, NEW YORK.

HANDLE.

No. 845,666.

Specification of Letters Patent.

Patented Feb. 26, 1907.

Application filed September 19, 1905. Serial No. 279,111.

To all whom it may concern:

Be it known that I, JOHN RUCKSTUHL, a citizen of the United States, residing at Fishkill-on-the-Hudson, in the county of Dutchess, State of New York, have invented certain new and useful Improvements in Handles; and I do hereby declare the following to be a full, clear, and exact description of the invention, such as will enable others skilled in the art to which it appertains to make and use the same.

This invention relates to handles for brushes or the like.

The object of the invention resides in the provision of a handle embodying such characteristics that it may be lengthened or shortened and whereby the device may be used without the employment of ladders or the necessity of standing on supports for reaching higher elevations.

With these and other objects in view the present invention consists in the combination and arrangement of parts, as will be hereinafter more fully described, shown in the accompanying drawings, and particularly pointed out in the appended claim.

In the drawings; Figure 1 is an elevation of my invention. Fig. 2 is a longitudinal sectional view.

Reference to the drawings will disclose that the brush or mop 1 is provided with a shank 2, designed to slidably fit in one end of a metallic or other sleeve 3 and that a wooden handle 4 is designed to slidably fit in the opposite end of the sleeve 3. This sleeve 3 is provided with slots 5 and 6 at opposite ends, and encircling the sleeve adjacent each slot is a metallic strap 7, the free ends of the straps being bent to provide pairs of spaced ears 8, between each pair of which is pivotally mounted a cam-lever 9 in any suitable manner. The upper cam-lever 9 is so arranged that its cam-face 10 may enter the upper slot 5 and engage the shank 2 of the mop or brush 1 and secure it against move-

ment with respect to the sleeve. The lower cam-lever 9 is adapted to pass through the slot 6 and engage the wooden handle 4 to hold the latter against accidental movement. It will be readily understood that by reason of the peculiar arrangement of the cams with respect to the sleeve and the mop or brush 1 and wooden handle 4 either of the last two mentioned elements may be adjusted longitudinally of the sleeve 1 as may be desired. 55

The metallic straps are so arranged with respect to the sleeve 3 that when the levers are drawn into engagement with the brush or mop and handle, or both, said straps are firmly held in place and cannot slide upon 60 the sleeve, thus obviating the necessity of positively securing said straps to the sleeve.

What is claimed is—

A device of the character described comprising a sleeve having a pair of unconnected, 65 longitudinal slots formed therein at opposite ends; a cleaning member having its shank slidably fitted in one end of the sleeve, and a handle member mounted in the opposite end thereof, said sleeve forming the sole 70 means of connection between said members; a strap encircling each end of said sleeve and slidably longitudinally thereon, the free ends of each strap being bent to form pairs of spaced ears; and a cam-lever pivotally 75 mounted between each pair of ears, and having its head working in the corresponding slot for engagement with the corresponding member, whereby said members may be separately adjusted longitudinally of the 80 sleeve, and held in adjusted position, said cam-levers further serving as the sole means for holding said straps upon the sleeve.

In testimony whereof I affix my signature in presence of two witnesses.

JOHN RUCKSTUHL.
